UNITED STATES PATENT OFFICE.

DEL ROY F. FOWLER, OF MELROSE, PENNSYLVANIA.

PORATABLE BATH.

No. 821,230.

Specification of Letters Patent.

Patented May 22, 1906.

Application filed May 15, 1905. Serial No. 260,554.

To all whom it may concern.

Be it known that I, DEL ROY F. FOWLER, a citizen of the United States, residing at Melrose, in the county of Montgomery and State 5 of Pennsylvania, have invented certain new and useful Improvements in Portable Baths, of which the following is a specification.

My invention relates to improvements in portable baths for infants and children; and 10 it consists of a collapsible receptacle or bag formed of a waterproof material and so appointed that it may be readily secured to the rim of an ordinary bath-tub or to a frame especially adapted to its purpose.

15 The nature of my invention will be more fully understood by reference to the accompanying drawings and to the description thereof as hereinafter presented.

Referring to the figures of the drawings, 20 Figure 1 illustrates a plan view of an ordinary type of bath-tub with my invention applied thereto. Fig. 2 represents a longitudinal section of the same, taken on a line 22 of Fig. 1. Fig. 3 shows a transverse section taken 25 on the line 33 of Fig. 2. Fig. 4 is a perspective view of one of the stay-rods employed in supporting the ends of the bag. Fig. 5 is a perspective view of a portion of the receptacle or bag, showing one of the supporting-hoops and the means for adjustably securing 30 the bag to the same. Fig. 6 illustrates my device as applied to a special form of supporting-frame; and Fig. 7 shows a detached perspective view of the stay-rods, showing 35 the manner in which they may be joined together.

Referring now to the reference-letters of the drawings, A represents a bath-tub of the conventional type, having faucets A' A' and 40 a waste-pipe A''. It also has an upper rim or flange A³, extending somewhat over the framework of the tub, to which the device forming the subject-matter of my invention is adapted to be fastened.

45 B is a bag, made of rubber, rubber-coated canvas, or other like waterproof material, provided at its upper sides and ends with open hems b and b' to receive detachable stay-rods C and C'. The receptacle or bag 50 B is also provided with a number of straps D, each of which is adapted to engage a buckle D', hinged to the hook D², which latter is formed so as to embrace the flange A³ of the bath-tub. The stay-rods C², which support 55 the ends of the bag B, are threaded at

their ends to enter correspondingly-threaded lower openings in the hooks D³, which, like the hooks D², are also fitted to embrace the flange A³ of the bath-tub.

In Fig. 6 I have illustrated my invention as 60 adapted to a special form of frame E, which may be employed in places where a bath-tub is not accessible. This frame is composed of cross-pieces E' E', &c., connected together by upper horizontal rods E² E² and a centrally-located horizontal rod E³, to which the cross-pieces are fulcrumed. Where a frame of this description is employed, I prefer to fasten the stay-rods C' and C² together by a coupling F, which, as shown in Fig. 7, is 70 threaded to engage both of said rods. The bag B is provided with a discharge-nozzle G and plug G', and where a frame such as shown in Fig. 6 is employed the lower threaded part of the nozzle G may be provided with 75 a rubber hose to fill or discharge the bag, as may be desired.

Having described my invention, what I claim, and desire to secure by Letters Patent, is—

1. The combination with a supporting-frame, of side and end stay-rods adapted to be secured thereto, a bag secured to the end stay-rods and hooks adjustably secured to the sides of the bag and adapted to engage 85 the supporting-frame.

2. The combination of a supporting-frame, of side and end stay-rods detachably secured together and adapted to engage the supporting-frame, a bag of rubber or like material secured at opposite ends to the stay-rods and hooks adjustably fastened to the sides of the bag and adapted to engage the supporting-frame.

3. The combination of a supporting-frame, 95 of long and short stay-rods threaded together and arranged within the supporting-frame, hooks connected to the ends of the short stay-rods and adapted to engage the supporting-frame, a bag secured at its ends 100 to the short stay-rods and provided along its sides with straps, and hooks adjustably secured to the straps and adapted to engage the supporting-frame.

In testimony whereof I affix my signature 105 in presence of two witnesses.

DEL ROY F. FOWLER.
